UNITED STATES PATENT OFFICE

104,835

DESIGN FOR A BOTTLE

John L. Dunnock, Baltimore, Md., assignor to Swindell Brothers, Incorporated, Baltimore, Md.

Application January 18, 1937, Serial No. 67,135

Term of patent 7 years

To all whom it may concern:

Be it known that I, John L. Dunnock, a citizen of the United States, residing at Baltimore city and State of Maryland, have invented a new, original, and ornamental Design for Bottles, of which the following is a specification, reference being had to the accompanying drawing, forming part thereof.

I claim:—

The ornamental design for a bottle substantially as shown.

JOHN L. DUNNOCK.
